UNITED STATES PATENT OFFICE.

PAUL L. HOFSTAD, OF MINNEAPOLIS, MINNESOTA.

FOLDING TABLE.

Application filed September 11, 1922. Serial No. 587,519.

To all whom it may concern:

Be it known that I, PAUL L. HOFSTAD, a citizen of the Kingdom of Norway, residing in Minneapolis, county of Hennepin, and 5 State of Minnesota, have invented certain new and useful Improvements in Folding Tables, of which the following is a specification.

This invention relates to new and useful 10 improvements in folding tables and more particularly relates to tables capable of being adapted for various uses.

The object of my invention is to provide 15 a folding table which when unfolded may be used as a picnic table, or a child's play table, and when partially folded may be used as a child's writing desk. It may also be folded in such a manner as to provide a very convenient and practical writing desk 20 when held upon the knees by an older person.

A further object is to provide a folding 25 table which when folded will form a very neat and compact box into which the usual picnic utensils, such as dishes, cutlery, table 30 cloth, napkins, etc., may be conveniently packed, thereby, also adapting it for use as an automobile picnic table, requiring but very little space when packed in a car.

35 A further object is to provide an apparatus of the class described of comparatively simple and inexpensive construction, and at the same time, very strong and durable.

Other objects of the invention will more 40 fully appear from the following detailed description and the accompanying drawings and will be pointed out in the annexed claims.

In the drawings there has been disclosed 45 a structure adapted to carry out the objects of the invention, but it is to be understood that the invention is not confined to the exact features shown, and various changes may be made within the scope of the claims 50 which follow.

In the drawings:

Figure 1 is a perspective view of the device adapted for use as a table;

55 Figure 2 is a perspective view showing the device adapted for use as a child's writing desk;

Figure 3 is a similar view showing the device partially folded and adapted for use as writing desk or table for an older person 60 when placed upon the knees.

Figure 4 is a similar view showing the table folded;

Figure 5 is a bottom view of the table showing the legs at one end unfolded while those at the other end are folded to lie flat 65 against the under side of the table top.

Figure 6 is a longitudinal sectional view of the device, as shown in Figure 1, and showing the simple method of unfolding the legs. 65

Figure 7 is a detailed sectional view of one of the hinges.

In the selected embodiment of the invention herein shown, for purposes of disclosure, there is illustrated a table having two 70 sections of any suitable material, preferably wood, each section comprising a top 8 and side rails 9, preferably grooved to receive the edges of the table top, as shown in Figure 1. Cross rails 11 are provided at the 75 outer end of each section and are secured to the underside of the table top and to the ends of the side rails 9 by any suitable means. Similar cross rails 12 are provided adjacent the inner edges of the two sections 80 and in like manner are secured to the underside of the table top, as shown in Figures 5 and 6.

The two table sections are connected together by suitable hinges 13, preferably secured to the inner side of the side rails 9 by suitable screws 14. Referring to Figure 7, it will be noted that the straps 15 of the 85 hinges are substantially above the joints or pivots in said hinges, said straps being arranged in aligned relation with each other and adapted to have their inner ends abut, as shown at 16, Figure 7, when the table is unfolded. This particular type of hinge also provides a very substantial connection 90 between the two table sections when unfolded to the position shown in Figures 1 and 6, keeping said sections in true alignment with each other and positively preventing the table top from sagging as a result of 95 continued hard use, or when heavily loaded. 100

A pair of suitable supporting legs 17 are 105 preferably provided at each end of the table, and rigidly connected together at their upper ends by a suitable cross member 18. These legs are pivotally connected to the side rails 9 by metallic strips or braces 19 in such a manner as to permit them to be folded against the underside of the table top, as shown on the right hand side of Fig- 110

ure 5. On the right hand side of Figure 6, I have shown the legs partially unfolded by full lines, while the dotted lines on this same side of the figure indicate the position 5 assumed when fully extended or unfolded. The legs on the left hand side of this figure are also shown in their unfolded position. Suitable wooden blocks 20 are preferably secured to the underside of the table top 10 adjacent each end and a suitable distance from the cross rails 11, thereby providing a gap between said rails and the blocks 20 adapted to receive the cross member 18 when the legs are in the position shown on 15 the left hand side of Figure 6. Thus, when the legs are unfolded, and the table is placed upon the supporting legs, the blocks 20 and braces 19 will positively prevent the legs from accidentally collapsing thus providing 20 a very rigid and substantial table.

When it is desired to collapse or fold the table, the legs are folded within their corresponding table sections, as above described, and the two sections are folded over, 25 as shown in Figure 4, thus forming a very neat and compact box in which the usual picnic utensils may be conveniently packed and carried in an automobile when the device is used as a picnic table. When used 30 for this purpose, the seat cushions of the automobile have been found to provide very practical and comfortable seats placed upon the ground about the table. The users may also sit upon the ground, the table being of 35 a suitable height to be conveniently reached from that position. The table may also be used as a child's play table in the nursery or playroom and when not in use may be folded up and stored away.

40 This table may also be converted into a child's writing desk, as shown in Figure 2, by merely folding the two sections with the legs in their unfolded position until the ends of the legs engage each other. The table is 45 then placed upon the floor resting upon the ends of the side rails 9 and the outer surface of the ends of the legs of one section, while the other section is supported in a slightly inclined position upon its supporting 50 legs. In this position the device provides a very useful and convenient writing desk for a young child.

It may also be adapted for use as a writing desk, or table for an older person when 55 folded, as shown in Figure 3, and held upon the knees.

The table may be made in various sizes or dimensions and of any suitable wood or other material that may be adapted for the

purpose, and of course, the exterior finish 60 may be of any grade or character desired.

I claim as my invention:

1. A table comprising two duplicate sections having their abutting edges hinged one upon the other transversely of the table and 65 adapted to be unfolded in substantial alignment one with the other, a pair of legs at each end of said table, each pair having a cross-bar between the legs, said table sections having cross-bars in the under side 70 thereof near their outer ends and blocks spaced therefrom forming recesses or seats to receive the upper ends of the pairs of legs, and the connecting cross-bars therefor, links pivotally connecting the upper portions of 75 said legs with said sections, said legs when disengaged from their seats folding with said links into recesses provided in the under side of said sections and being concealed when the sections are folded over one upon 80 the other.

2. A table comprising sections hinged one upon the other transversely of the table and adapted to be unfolded into substantial alignment one with the other, a pair of legs 85 at each end of said table, each pair having a cross-bar between the legs, the table sections having cross-bars in the under side thereof and blocks spaced therefrom forming recesses or seats to receive the upper 90 ends of the pairs of legs and the connecting cross-bars, links pivotally connecting the upper portions of said legs with fixed pivots on said sections, said pairs of legs when disengaged from their seats being partially 95 revolved so that their lower ends are at the outer ends of the sections and their upper ends adjacent the hinges of the sections, and said legs fitting within the sections and concealed when the table is closed. 100

3. A table comprising top sections hinged together at one edge transversely of the table, and having recesses formed in the under side thereof, said sections when extended being in substantial alignment with each other, legs arranged in pairs at the outer ends of 105 said section and loosely fitting within seats provided in the under side of said sections, links pivotally connecting the upper portions of said pairs of legs with fixed pivots 110 on said sections, said legs when folded being adapted to fit within said recesses with their upper ends at the inner ends of said sections and their lower ends at the outer ends of said sections. 115

In witness whereof, I have hereunto set my hand this 5th day of September 1922.

PAUL L. HOFSTAD.
